UNITED STATES PATENT OFFICE

CLARENCE L. DEWEY, OF ELKHART, INDIANA, ASSIGNOR TO OUTING MANUFACTURING COMPANY, OF ELKHART, INDIANA, A CORPORATION

BANJO

Application filed April 12, 1926. Serial No. 101,305.

This invention relates to musical instruments and more particularly to an improved banjo wherein the neck is secured to a housing comprising upper and lower sections, 5 separated by a suitable felt pad to prevent vibrations and chattering, the said upper section formed with an integral flange having sound outlet openings therein while the upper portion of the upper housing section is 10 provided with an integral annular bead or rib over which the diaphragm or skin head is stretched to afford a dead air space under the head adapted to kill over-tones.

It is an object of this invention to provide 15 an improved banjo or similar instrument with abutting housing sections, one of which is provided with suitable sound outlet openings.

It is also an object of this invention to provide 20 a banjo wherein the upper housing section or body is provided with an integral outwardly directed sound escaping flange and with an integral inwardly directed corrugated portion over which the skin head is 25 adapted to be stretched.

It is an important object of this invention to provide an improved banjo or similar instrument of simplified construction and adapted to be readily assembled with the 30 casing or upper body section, being constructed to afford an apertured beaded flange for receiving the lower body section and with an integral corrugated portion over which the skin head is adapted to be stretched with 35 said corrugated portion affording a dead air space tending to overcome over-tones.

Other and further important objects of 40 this invention will be apparent from the disclosures in the specification and the accompanying drawings.

This invention (in a preferred form) is illustrated in the drawings and hereinafter more fully described.

45 On the drawings:

Figure 1 is a top plan view of a banjo embodying the principles of this invention with a portion of the neck broken away.

50 Figure 2 is a longitudinal vertical section of the banjo taken on line II-II of Figure 1

with parts shown in elevation and with parts broken away.

As shown on the drawings:

The reference numeral 1 indicates a banjo finger board having an integral neck portion 2 provided with a recess 3 for receiving the reduced end 4 of a dowel 5 which acts as a brace member. Enclosing the dowel 5 and secured to the neck portion 2 is a metal casing or upper body section 6, the upper margin of which is curled or bent inwardly to afford an outer ring or bead 7 and an inner annular tone bead or rib 8 disposed in a plane slightly higher than the plane of the outer bead 7. The two beads 7 and 8 afford a groove or 65 space 9 therebetween.

Stretched over the tone bead 8 is a diaphragm or skin head 10 the outer portion of which passes over the outer bead or rib 7 and is engaged around a flesh wire or annular 70 ring 11. Engaged around the upper portion of the upper casing section above the wire ring 11 is a retaining band or hoop 12. Movably engaged on the retaining band or hoop 12 are a plurality of equidistantly spaced tensioning screw hooks 13 the lower ends of which are threaded for the purpose of receiving bolts or nuts 14. Mounted upon the skin head 10 is the usual bridge 14^a and a plurality of strings 15 which extend from the outer end of the finger board across the skin head and are connected to the tail-piece 16 which is held in place by means of a tail-piece bolt 17. With the skin head 10 stretched over the upper portion of the upper casing 80 section 6 as described, the outer portion of the skin head closes the groove 9 thereby tending to form a dead air space under the outer portion of the head which serves to eliminate over-tones. As clearly illustrated in Figure 2 the upper casing section 6 is secured to the outer end of the dowel 5 by means of a screw 85 18 or other suitable means.

As clearly illustrated in Figure 2 it will be noted that the lower margin of the upper 90 casing section 6 is formed to provide an integral outwardly directed flange or ring 19, the margin of which is rolled downwardly and upwardly to afford an annular rim or bead 20. The inner margin of the outer bead 100

20 stops short of the under face of the flange 19 to permit an annular felt washer or pad 21 to be seated against the under surface of said flange with the outer margin of the washer projecting into the bead 20. The 5 flange 19 is provided with a plurality of sound escape openings 22, 23, and 24 of different sizes. It will of course be understood that the number, shape and size of the sound escape openings or apertures in the upper casing section flange 19 may be varied as desired. Seated against the under surface of the upper casing section flange 19 where it joins the upper casing section 6 is a metal 10 strengthening ring or continuous washer 25 having a plurality of spaced apertures therein to permit the lower threaded ends of the retaining hooks 13 to project therethrough for the purpose of receiving the retaining nuts 14. The retaining hooks 13 project through suitable apertures 26 provided at spaced intervals around the inner marginal portion of the flange 19. It will thus be seen that by threading the nuts 14 onto the lower ends of the 15 hooks 13 that the retaining bead or ring may be secured in position to cause adjustment of the skin head 10. The washer ring 25 acts not only as a washer for the nuts 14 but serves the additional purpose of greatly 20 strengthening the upper body section of the banjo. As shown in Figure 2 the lower threaded portion of the tail-piece bolt 17 projects through suitable apertures in the flange 19 and in the washer ring 25 and has a nut 25 27 engaged on the lower end thereof for the purpose of holding the tail-piece securely in position.

Positioned beneath the upper casing section 40 6 is a lower casing section 28 of concave shape having the middle portion thereof depressed to form an apertured socket or pocket 29 through which a retaining screw 30 projects with the inner end of said screw engaged in the dowel 5 to removably hold the lower 45 casing section 28 secured in position. If desired the lower casing section 28 may be provided with a plurality of openings 31 to permit access to be had to the nuts 14 of the retaining hooks 13 without requiring the removal of the lower casing section 28 from engagement with the upper casing section. Integrally formed on the outer margin of the lower casing section 28 is an upwardly directed rim or cylindrical wall 32, the edge of 50 which seats against the felt washer or pad 21 to the inside of the annular outer bead 20. The felt pad or ring 21 thus serves as a means to prevent vibrations or chattering when the instrument is played.

60 It will of course be understood that if desired the openings 31 in the lower casing section may be omitted, in which case the nuts 14 may be readily adjusted by simply removing the retaining master screw 30 to permit removal of the lower casing section 28.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A banjo comprising a finger board, a neck formed thereon, an upper casing section secured to said neck, a plurality of concentric ribs integrally formed on the upper portion of said casing section, a skin head disposed over said concentric ribs, means for tensioning the skin head with said skin head serving to form a dead air space between said concentric ribs, a bridge disposed on said head, strings positioned above the finger board and passing over said bridge, a tail-piece on said upper casing section to which the strings are attached, an apertured outwardly directed flange integrally formed on said upper casing section, an apertured continuous reinforcing washer engaged against said flange, hook bolts for tensioning the skin head and projecting through said apertured flange and through said continuous reinforcing washer, a felt pad positioned against said apertured upper casing section flange, and a lower casing section removably secured in position against said pad.

2. In a banjo, an upper sheet metal casing consisting of a cylindrical portion having an upper inturned flange substantially at right angles to the cylindrical portion and having a lower outwardly directed perforated flange substantially at right angles to said cylindrical portion, a membrane, means for stretching said membrane over said upper inturned flange, a lower casing member having a telescopic relation with said outwardly directed flange, and a neck secured to said upper casing and supported upon said outwardly directed flange.

3. In a banjo, an upper sheet metal member having a substantially cylindrical body portion with an upper inturned flange substantially at right angles to the body portion to provide a stretching seat for a membrane, a membrane, means for stretching said membrane over said seat, said sheet metal member having a lower outwardly directed perforated flange, a neck supported upon said outwardly directed flange and secured to said member, and a lower sheet metal member having an outwardly directed flange in fitting relation with said outwardly directed flange and means for removably securing said lower member in such fitting relation.

4. In a banjo, an upper annular metal member having an upper inturned flange so formed as to provide a stretching seat, a membrane, means for stretching said membrane over said seat, a dowel extending transversely of said member, said metal member

having an integral lower outwardly directed perforated flange, a lower member, a screw for securing said lower member to said dowel, said upper member and lower member having 5 interfitting parts adapted for centering said lower member for inserting said screw, and a neck secured to said member and resting upon said outwardly directed flange.

5. In a banjo, an upper annular metal 10 member having an inturned flange so formed as to provide a membrane stretching seat, a membrane, means for stretching said membrane over said seat, said member having an integral outwardly directed perforated 15 flange, a transverse dowel in said member having a threaded aperture, a lower member having a screw aperture, a rim interfitting with the first member for centering said lower member for aligning said apertures, and a 20 screw for securing said lower member to said dowel.

In testimony whereof I have hereunto subscribed my name.

CLARENCE L. DEWEY.
